UNITED STATES PATENT OFFICE.

HARRY CLIFFORD WALLIS AND KEITH ALEXANDER ROBINSON, OF LONDON, ENGLAND.

CAP CLOSURE FOR THE MOUTHS OF BOTTLES OR OTHER CONTAINERS.

Application filed August 11, 1926, Serial No. 128,611, and in Great Britain April 30, 1926.

This invention relates to cap closures for the mouths of bottles and other containers and refers more particularly to cap closures of the kind which comprise a closure element 5 for covering the mouth of the container and a fastening element for holding said closure element in situ said fastening element consisting of a metallic band strip bent into a ring with its two ends fastened together by 10 means of a tongue and slot connection and adapted to be applied around the neck of the container in such a way that its two ends must be unfastened before either it or the closure element can be removed.

15 It is frequently desirable (as when the cap closure is adapted to cover a milk bottle) that said cap closure having been removed from the container should not be susceptible of being replaced and various means have been 20 proposed for ensuring that once said cap closure is in situ the tongue and slot connection of said band strip can only be unfastened by destruction.

The object of the invention is the provision 25 of improved means for ensuring this in a simpler manner than heretofore and one which will permit of band strips of small breadth being constructed.

The invention consists broadly in the arrangement according to which the tongue and 30 slot connection is such that (except by destruction) the tongue can only be disengaged from the slot by twisting the band strip so that its two ends are transverse to one another. When the cap is in situ this becomes 35 impossible since the strip is more or less tight on the neck of the container.

In order that the invention may be the better understood a cap closure in accordance 40 therewith is illustrated in the accompanying drawings, wherein

Figure 1 is an elevation of band strip as blanked out.

Figure 2 is a perspective view of the same 45 shown before association with the closure element and nearly in the position at which the tongue at one end thereof may be engaged or disengaged from the slot at the other end.

Figure 3 is a sectional elevation of the complete cap closure shown in situ over the 50 mouth of a bottle.

Referring to the drawings the closure element takes the form of a disc or cap 6 and the metallic band strip 2 has its upper edge 55 inturned as at 2^a so as to engage said top as

shown in Figure 3 so that said top and strip together constitute a cap of pill box formation. The lower edge of said strip after such cap is placed in situ over the mouth of the bottle is adapted to be inturned also as at 2^b 60 so as to engage under the overhanging shoulder 5 formed around the neck of the bottle. The tongue 1 of the strip 2 extends from one extremity thereof and has a reduced neck 3. The slot 4 takes the form of a hole adjacent 65 the other extremity, which hole is of greater dimension longitudinally than laterally of the strip. The neck 3 of the tongue is narrower than the lateral dimension of the hole and is therefore small enough to pass through 70 the slot 4 when the two ends of the strip are in a straight line with one another but the remainder of the tongue, while being narrower than the longitudinal dimension of the hole is wider than the said lateral dimension of 75 the hole. That is to say said remainder of the tongue is too wide to be passed through the hole 4 except by twisting the strip a little more than shown in Figure 3 so that the two ends thereof are transverse to one another. 80 When making the cap this can of course be done but once the cap is secured in situ over the mouth of the container with the lower edge of the strip inturned under said shoulder 5 the strip can no longer be thus twisted 85 as this would involve a reduction of the effective circumference, which reduction is rendered impossible by said bottle neck. For removing the strip therefore the tongue must be broken off. In the embodiment shown the tongue is of spear head formation and the slot takes the form of a triangle similar to but slightly smaller than the spear head end. The exact form of the slot and tongue illustrated is obviously not essential.

What we claim and desire to secure by Letters Patent is:—

1. A cap closure embodying therein an annulus formed of a narrow strip of sheet metal, the ends of said strip being united by a tongue having a reduced neck, at one end of the strip, and a slot adjacent the other end of the strip, said slot being in length greater than, and in width less than, the width of said tongue, and the portion of said slot adjacent the end of the strip being relatively wider than the neck of said tongue, and said tongue being exposed outwardly of the annulus, whereby slight expansion of the lower edge of the annulus is permitted when apply- 105 110

ing the closure to, and the breaking off of the tongue is necessary when removing the closure from, a bottle.

2. A cap closure embodying therein an annulus formed of a narrow strip of sheet metal, having an inturned upper edge adapted to engage a disk, the ends of said strip being united by a tongue having a reduced neck, at one end of the strip, and a slot adjacent

10 the other end of the strip, said slot being in length greater than, and in width less than, the width of said tongue, and the portion of

said slot adjacent the end of the strip being relatively wider than the neck of said tongue, and said tongue being exposed outwardly of 15 the annulus, whereby slight expansion of the lower edge of the annulus is permitted when applying the closure to, and the breaking off of the tongue is necessary when removing the closure from, a bottle. 20

In witness whereof we affix our signatures.

HARRY CLIFFORD WALLIS.

KEITH ALEXANDER ROBINSON.
